UNITED STATES PATENT OFFICE.

GEORGE A. AMEDICK, OF DARIEN, NEW YORK.

SEPARATOR.

1,101,775.

Specification of Letters Patent. Patented June 30, 1914.

Application filed May 20, 1912. Serial No. 698,392.

To all whom it may concern:

Be it known that I, GEORGE A. AMEDICK, a citizen of the United States, residing at Darien, in the county of Genesee and State 5 of New York, have invented a new and useful Improvement in Separators, of which the following is a specification.

This invention relates to improvements in separators and more particularly to separators 10 or screens of the kind used in bean threshing machines or the like.

The objects of this invention are to provide separators of this kind with agitating or stirring means of simple and practical construction for moving the material to be separated over the face of a screen to insure a thorough separation of the seed or grain from the straw, vines or pods and prevent the clogging up of the separator by the material to be separated; also to provide separators of this kind with improved means for preventing the loss of seed or grain through the discharge end of the machine; also to improve separators of this kind in the respects hereinafter more fully specified.

In the accompanying drawings, consisting of two sheets: Figure 1 is a fragmentary side elevation of a threshing machine provided with a separator embodying the invention.

Fig. 2 is a fragmentary longitudinal sectional elevation thereof. Fig. 3 is a plan view, partly in section, showing the separator and agitating device. Fig. 4 is a fragmentary side elevation, taken on the side of the machine opposite to that shown in Fig. 1, of a part of the actuating mechanism for the agitator of the separator. Fig. 5 is a sectional plan thereof on line 5—5, Fig. 4. Fig. 6 is an elevation thereof partly in section, on line 6—6, Fig. 4. Fig. 7 is a fragmentary elevation of the guiding means for the agitator of the separator. Fig. 8 is a plan view thereof. Figs. 9 and 10 are fragmentary elevations of the pivoted guide devices, showing different positions of these parts. Fig. 11 is an enlarged perspective view of a part of the guiding means.

Like reference characters refer to like parts in the several figures.

The invention is herein described in connection with a bean or pea threshing machine, but it will be understood that it is not limited to this use and could readily be applied to separators for other material. For 55 the sake of brevity, the beans, peas or grain which is to be separated from its straw and

chaff will be hereinafter referred to as "beans."

A represents the frame of a threshing machine which is equipped with any usual or suitable threshing mechanism (not shown). The beans which are threshed from the pods drop on an inclined shoe or platform B by which they are delivered to a screen b. A part of the beans pass through this screen 65 into a trough or receiver b' while the remainder of the material passes over the screen and, together with other beans and chaff subsequently removed from the straw by a second threshing device, are delivered 70 by a shoe or plate C to a separator which is mounted on the rear portion of the frame A. This separator comprises the usual screen D secured on a shoe E which is adapted to be shaken or reciprocated lengthwise of the 75 machine, for instance, by a rock shaft e which has an arm e' engaging the shoe E and a rock arm e² which is connected to a pitman e³ from which it receives its rocking motion. The material while in the separator is subjected to an air blast from a suitable fan or blower F by which the chaff and other light impurities are blown out through the discharge end of the machine, while the beans drop on the shoe E and pass 85 into a tube or conveyer G, located below the shoe. All of these parts of the threshing machine, except as hereinafter specified, may be of any usual or suitable construction and constitute no part of this invention. 90

In order to prevent the clogging up of the screen D and thus necessitating the stopping of the machine and the cleaning out of the screen, which causes considerable delay, means are employed for agitating and stirring the material on the screen. In the construction shown, an agitator arm or sweep H is provided for this purpose which extends lengthwise of the machine above the screen and is adapted to sweep across the 100 same from side to side. This sweep H is preferably rigidly secured by means of a suitable connecting piece h to a bar or pole h', one end of which is suitably pivoted at h² on the front axle or other part of the frame of the machine. The bar h' and the sweep H secured thereto are adapted to swing on the pivot h² so that the sweep H passes over the screen and thereby thoroughly agitates or stirs up the material on the screen. Since the sweep H swings from the pivot h², the corners of the screen nearest 105 110

to the pivot will not be reached by a straight sweep, and the sweep is therefore preferably provided with side arms h^3 h^3 which are secured to the main sweep arm H and extend outwardly and rearwardly to each side thereof.

To prevent the sweep H from piling up the material on each side of the screen or throwing it sidewise off of the screen, means are preferably provided for lifting the sweep up from the screen before it reaches the end of its movement and carrying it over the material which has been shoved across the screen by the sweep, and then lowering the sweep to the screen at the outer or far side of the material when the arm reaches the end of its movement. This is accomplished in the construction shown by providing the rear end of the bar h' with an anti-friction roller I which is adapted to travel on a suitable guide or track comprising a substantially horizontal guide rail i, and inclined guide plates K, at the ends of the rail i, upon which the roller is adapted to travel to raise the sweep H up from the screen D as it approaches the end of its movement in each direction. These guide plates are pivoted at k k on the frame of the machine above the ends of the guide rail i and each is provided with a slot k' through which the roller I is adapted to drop back to the rail after reaching the end of its travel to again lower the sweep H onto the screen. On the return movement the roller passes underneath the plates K, which swing on their pivots to permit the roller to pass by. The path of movement of the roller will therefore be as indicated by dotted lines in Fig. 7 and the agitator sweep will have a corresponding movement over the upper face of the sieve. The movement causes the material to be scraped by the arm H almost to the edge of the screen, whereupon the arm is raised and carried over to the outer side of the pile of material and then moves the pile back over the screen to the opposite side, where a similar operation is repeated. This movement of the sweep prevents the accumulation of material on the sides of the screen and the scattering of the same over the side edges of the screen. Any suitable means may be employed for reciprocating the agitator bar. For example, a shaft L, driven by the threshing mechanism through a pulley and belt l Figs. 4 and 5, is provided with a pinion l' which meshes with a gear l'' secured to one end of a shaft l^3 . This shaft l^3 extends transversely across the machine and is provided at its opposite end with an arm or crank l^4 which is connected by a pitman l^5 to one arm of a lever l^6 which is pivoted on the frame of the machine and which has another arm connected by a rod l^7 with the swinging bar h' , whereby motion is transmitted from the crank arm to

the agitator. The movement of the agitator sweep across the face of the screen absolutely prevents the clogging of the same and also expedites the separation of the material. The action of the agitation against the screen helps to remove any pods or other material adhering to the beans.

Provision generally has to be made in separators of this kind for preventing any of the beans from being blown over the screen and out through the discharge end of the machine by the current of air from the fan. For this purpose an inclined baffle plate M extending transversely of the machine at the rear end of the screen is ordinarily provided against which the beans strike and drop into a conveyer trough m below the baffle plate. This baffle plate usually has only a slight inclination so as to prevent the accumulation of chaff in the trough, but such an arrangement permits some of the beans to be blown out of the machine over the inclined plate. To avoid this objection, the plate in the present machine is given a greater inclination or pitch and a mechanically operated device N is provided to prevent the clogging up of the space between the plate and the shaking shoe E. The device N, shown in the drawings, consists of a rocking bar or rod which extends transversely of the machine in the space between the shoe E and the baffle plate and is provided with a plurality of tines or teeth n crossing said space. The bar N is journaled at its ends on the side walls of the shaking shoe E and has a rigid arm n' at one end thereof outside of the machine which is pivoted to a link n² which is secured to a stationary or rigid part of the frame. The reciprocation of the shoe in the frame of the machine causes the toothed bar N to rock or oscillate in the space between the shoe and the baffle plate and thus loosen or agitate the chaff and straw therein so that the blast of air can easily carry the same out through the discharge opening of the machine and prevent them from collecting in and choking said space. The inclination of the baffle plate can therefore be made great enough to prevent the beans from being blown out of the machine.

I claim as my invention:

1. In a separator, the combination with a separating screen, of a sweep arranged to move to and fro over the surface of said screen, and means cooperating with said arm for raising the same away from the surface of said screen before the sweep reaches the limit of its travel in each direction and then lowering the sweep again toward the surface of the screen, substantially as set forth.
2. In a separator, the combination with a screen, of a sweep pivoted to oscillate over the surface of said screen, means for swing-

ing said sweep on its pivot, and means co-operating with said arm for raising the same away from the surface of said screen before the sweep reaches the limit of its 5 travel in each direction and then lowering the sweep again toward the surface of the same, substantially as set forth.

3. In a separator, the combination with a screen, of a sweep arranged to oscillate over 10 the surface of said screen, a pivoted bar to which said sweep is secured, means for swinging said bar, guiding means coöperating with said bar for raising said sweep away from the surface of said screen before 15 the sweep reaches the limit of its travel in each direction and then lowering the sweep again toward the surface of the screen, substantially as set forth.

4. In a separator, the combination with a 20 separating screen, of a sweep arranged to move to and fro over the surface of said screen, a roller connected with said sweep, a guiding face over which said roller is adapted to travel, inclined parts over which 25 the roller is adapted to pass near the end of its movement, and means for permitting the roller to drop from said inclined parts to

said guiding face at the end of the movement of the roller and pass beneath said inclined parts in its return movement, substantially as set forth. 30

5. In a separator, the combination with a screen, of a sweep arranged to oscillate over the surface of said screen, a pivoted bar to which said sweep is secured, means for 35 swinging said bar, a roller secured on said bar, a guiding face over which said roller is adapted to travel, inclined plates pivoted near the ends of said guiding face upon which said roller is adapted to travel to 40 raise the sweep from the screen and from which the roller is adapted to drop onto the guiding face to lower the sweep onto the surface of the screen, said pivoted plates being adapted to rise to permit the passage 45 of said roller beneath them, substantially as set forth.

Witness my hand, this 11th day of May, 1912.

GEORGE A. AMEDICK.
